(57) **CLAIM**

The ornamental design for an exterior single hung extrusion for windows, as shown and described.

DESCRIPTION

FIG. 1 is an isometric front view of an exterior single hung extrusion for windows, according to the present disclosure. FIG. 2 is a top view of the exterior single hung extrusion for windows of FIG. 1.

FIG. 3 is a bottom view of the exterior single hung extrusion for windows of FIG. 1.

FIG. 4 is a front view of the exterior single hung extrusion for windows of FIG. 1.

FIG. 5 is a rear view of the exterior single hung extrusion for windows of FIG. 1.

FIG. 6 is an enlarged left side view of the exterior single hung extrusion for windows of FIG. 1; and,

FIG. 7 is an enlarged right side view of the exterior single hung extrusion for windows of FIG. 1.

The exterior single hung extrusion for windows is shown with two parallel dash-dash break lines that represent the bounds of the claim. The appearance of any portion of the article between the dash-dash break lines forms no part of the claimed design.

1 Claim, 4 Drawing Sheets
